TYPEWRITING MACHINE

Ernest M. R. Borg, Hartford, Conn., assignor to
Underwood Elliott Fisher Company, New York,
N. Y., a corporation of Delaware

Application April 19, 1935, Serial No. 17,169

12 Claims. (Cl. 197—81)

This invention relates to typewriter-case-shift mechanism, and aims to provide improved means for easily adjusting and quietly arresting the case-shifts, and which means will be simple so as to conduce to economical manufacturing and servicing, and be efficient and durable in use.

The improved means comprise a simple strip bent into elongately U-shaped form, which may be tempered, and mounted so that the resilient extremities thereof project from a support and are disposed between opposite stops for quiet case-shift-arresting engagement with the latter. For adjustment relative to said resilient extremities, said stops are screw-studs and are retained in novel sockets arranged to permit ready loosening and tightening of said stop-studs in connection with their adjustment, and to hold the studs securely to prevent derangement of the adjustment. The support or seating of said U-shaped resilient member may be made at an incline, so that forward or rearward shift of said member will effect its bodily adjustment up or down, thereby to provide for adjustment of the case-shift zone independently of adjustment of said stop-studs.

These devices may be at the front of side-members of a platen-shifting frame, such as the Underwood.

Other features and advantages will herein-after appear.

In the accompanying drawing,

Figure 1 is a section side view of the carriage-mechanism including the improved case-shift-arresting means.

Figure 2 is a perspective view of the typewriter-carriage and the present improvements.

Figure 3 is a perspective view of parts of the case-shift stop-devices at the front of the platen-frame.

Figure 4 is a fragmentary partly sectioned top plan view, showing details of the novel case-shift stop-device assembly.

In the Underwood machine a carriage-frame 11 runs upon a rear track 12 and a front track. A platen 13 is journaled in a frame 14, supported in said carriage-frame 11, for case-shifting movements, by means of side-arms 15 that are fastened to a cross-shaft 16 to work in unison about pivot-studs 16^a retained in said carriage-frame 11. Said side-arms 15 support the platen-frame 14 at gudgeons 18 of the latter, and side-links 19, connected to the carriage-frame 11, co-operate with said side-arms 15 to guide the platen-frame case-shift movements. The usual key-controlled case-shift rail and its frame are

shown at 20, Figure 1, the shift-rail engaging a roller 21 of the platen-frame. Ears 17, extending laterally from the sides of the platen-frame, may co-operate with the novel means to be described presently, to determine the lower-case position of the platen-frame, and may abut the carriage-frame at 17^a.

The carriage moves for letter-feeding at actuation of the usual type-bars represented at 23, and having upper and lower case types 23^a, Figure 1.

The improved means for regulating the range of case-shift movement of the platen-frame 14 and for arresting said movement quietly will now be described.

Each platen-frame side-member 25 presents a pair of adjustable case-shift stop-screws 26 having heads 27 forming the opposite stop-faces. Said stop-screws 26 are retained in novel sockets arranged so that each screw may be easily freed in its socket preparatory to its adjustment, and as easily secured after the adjustment. For this purpose, strips or tongues 28 extend from the platen-frame side-members 25, and are reflexly bent to form loops or split sockets 29 which may be threaded for receiving the stop-screws 26. The socket-forming tongue 28 affords an end-portion 30 against which a headed clamp-screw 31 may be drawn to contract the loop or socket 29, and thereby securely hold the stop-screw 26. Upon loosening said clamp-screw 31, the socket 29 will expand by its resiliency, for freeing the stop-screw 26 preparatory to its adjustment. The opposite socket-forming tongues 28 for each platen-frame side-member 25 are preferably part of a separate U-shaped sheet-metal piece 32 fastened, after forming of the sockets, to the platen-frame side-member 25, as by rivets 33. It will be noted that said clamp-screws 31 are easily accessible, that loosening or tightening the same does not itself disturb, and thereby facilitates, the adjustment of the stop-screws 26, and that the adjustment of the latter is securely maintained against accidental derangement inasmuch as the stop-screws 26 cannot accidentally become loosened.

Novel abutments on the carriage-frame 11 for engaging the platen-frame stops 27 are arranged to muffle the noise of impact, and, for this purpose, are formed by tabs 35, which, for sound-muffling resiliency, extend beyond supporting means on the carriage-frame. In order to facilitate the mounting and conduce to the sound-muffling action of said tabs 35, there is preferably an individual tab for each stop 27, and the

tabs 35 for each pair of stops 27 are spaced and are moreover unified by forming them as the extremities of a resilient elongately U-shaped single abutment-element 36 shown by itself in Figure 3.

Said abutment-element 36 may be inexpensively made of a strip of spring steel. The flat extremities or tabs 35 of said abutment-element 36 may face the platen-frame stops 27 squarely, while, by means of bends at 37, Figure 3, the body-portion of said abutment-element may be inclined to correspond with an inclined, preferably single, groove 38, in the carriage-frame 11, in which the abutment-element is seated. Adjustment of said abutment-element 36 along said inclined groove 38 will effect up or down adjustment of both its tabs 35, to regulate the case-shift zone independently of the platen-frame stop-screws 26, or, in other words, without individually adjusting the latter.

A pad or block 40, separately shown in Figure 3, may be disposed, as shown at Figures 1 and 2, between the spaced legs of the abutment-element 36 to support the latter against undue flexing when the projecting tabs 35 are engaged by the platen-frame stops 27. A screw 41, and a clamp-plate 42 which may engage both legs of the abutment-element 36, co-operate to secure the latter in its adjusted position in the groove 38, said screw 41 passing through said plate 42 and through the block 40 and being entered into a hole 43, Figure 3, of the carriage-frame 11. The clamp-plate 42 may have flanges 44 to engage the sides of the abutment-element 36 to prevent turning of said clamp-plate.

Adjustment of either main carriage-stop, which is divided into two abutments 35, may be effected independently of the upper and lower individual platen-frame stops 27, so that if the mechanic, after once adjusting said individual stops 27, should find that the types are erroneously striking the platen at a level or zone which is a little too high or a little too low at either end of the platen, he can correct the fault by adjusting either one or the other of the main stops 35. For effecting this main stop adjustment, he does not need to disturb the pre-adjustment of any of the four individual stops 26, but he simply loosens the fastening screw 41, then slides the main stop or loop diagonally along the inclined groove or slot portion 38 in the carriage, while keeping the abutments 35 level, until the two abutments 35 are raised or lowered to the exact point necessary, whereupon he can refasten the screw 41, and clamp the washer 42, the filler-block 40, and the main abutment-loop 36, to the grooved portion 38 of the carriage 11. Thus the platen is brought into exact type-face alignment by readjusting one or both of the main abutments, and without disturbing the setting of the stops 27, so that none of said individual stops has to be reset.

The stops 27 are in the form of screws which are carried by jaws 32, one on each end 25 of the platen-frame; the screws being secured fully adjustable by fastening screws 31.

The invention is not limited to yielding main abutments 35, 36, but preferably each is made in the form of a loop to give the tabs 35 thereof a yielding quality for securing quietness, as explained.

The sides of the groove 38 abut the companion outer sides of the body-portion of the abutment-element 36. The depth of said groove 38 may be shallow relatively to the width, face-

wise, of the abutment-element, as indicated, inasmuch as the spread of the legs of the abutment-element upon the seat of the groove and the union of said legs at 45 provide for stable support of the abutment-element, it being understood that, for noise-deadening resiliency, the tabs 35 project, substantially as shown, beyond the support afforded by the groove 38, block 40, clamping screw 41 and plate 42.

The stop-screws 26 may have screw-driver slots 46. It will be seen that the frictional embrace of the split sockets 29, easily tightened by the clamp-screws 31, effectively guards against the liability of said stop-screws 26 accidentally working loose. Nor can the stop-screws 26, after being turned to their proper adjustment, be deranged by tightening the embrace of the sockets 29 by means of the clamp-screws 31, it being understood that said embrace may be eased by means of said clamp-screws 31 to permit the turning or adjustment of the stop-screws 26, and that, for facilitating the adjustment, there may remain sufficient tightness of the embrace to prevent all end play of the stop-screws in the sockets.

The clamp-screws are shown threaded into the platen-frame side-member 25, as indicated at 47, Figure 4, and it will be understood that the tongue-portion 30 of the socket has a clearance hole for the body of the clamp-screw 31. The split sockets 29 can be inexpensively produced since they are formed from the sheet-metal strips or tongues 28, which may be part of the sheet-metal piece 32 which combines two of the sockets into a unit.

Variations may be resorted to within the scope of the invention, and portions of the improvements may be used without others.

Having thus described my invention, I claim:

1. In a typewriter having upper and lower case types, a case-shift mechanism including, in combination, a case-shiftable frame, a pair of opposite case-shift stops for limiting the case-shifting of said frame, an abutment-element formed by a strip bent facewise in elongately U-shaped form, and a support having a groove, inclined to said stops, for retaining said abutment-element in inclined transverse relation of its two legs to and between said opposite stops, the extremity of each leg extending beyond said groove to coat facewise resiliently and quietly with one of said stops, said opposite stops being adjustable relatively to one another to determine the extent of the zone of case-shift movement, and the abutment-element being independently adjustable, by a shift along said inclined groove, for adjusting said zone relatively to the printing-line of said types.

2. In a typewriter including a platen and a set of type-carriers, each type-carrier having a plurality of types; a stop-device for quietly arresting the opposite relative case-shift movements of said platen and set of type-carriers, said stop-device including two pairs of opposite individually adjustable stops; and, for sound-muffled engagement with said individual stops, a pair of resilient U-shaped abutment-elements, each presenting two spaced abutment-tabs, one for each individual stop, and inclined supporting means arranged to retain each of said abutment-elements, said abutment-tabs projecting beyond the supporting means and transversely of and between said opposite individual stops, to coat quietly with the latter, each abutment being adjustable bodily along its said inclined support,

- to vary the zone at which the types strike the platen, without disturbing the adjustment of any of said individual stops.
3. In typewriter-carriage mechanism, the combination with a platen, a carriage-frame, and a platen-frame supported by the carriage-frame for opposite case-shift movements relative to upper and lower case types, of a stop-device for quietly arresting said case-shift movements, said 10 stop-device including two individual stops on each end of the platen-frame, and, for sound-muffled engagement with each said two stops, a single U-shaped resilient abutment-element presenting two spaced parallel legs having bends so 15 as to terminate in parallel abutment-tabs inclined to the legs, one tab for each stop, and an inclined grooved or slotted support for said legs along which said abutment-element is adjustable to vary the point at which the types strike the 20 platen, said tabs projecting beyond said support and transversely of and between said opposite individual stops, to coact quietly with the latter, said grooved support being incorporated with said carriage-frame.
- 25 4. In a typewriter arranged for quiet operation, said typewriter including a platen and a set of type-carriers, each type-carrier having a plurality of types; a stop-device for quietly arresting the opposite relative case-shift movements 30 of said platen and set of type-carriers, said stop-device including two pairs of opposite individual stops, and, for sound-muffled engagement with said individual stops, resilient abutment-elements, each presenting two spaced parallel legs terminating in parallel abutment-tabs, one for each individual stop, each tab being 35 inclined to its leg, and inclined supporting means arranged to receive said legs to retain said abutment-elements, so that said abutment-tabs extend 40 beyond the supporting means and transversely of and between said opposite stops, to coact quietly with the latter, each of said abutment-elements being adjustable independently along said inclined supports for the purpose specified.
- 45 5. In a typewriter including a platen and a set of type-carriers, each type-carrier having a plurality of types; a stop-device for quietly arresting the opposite relative case-shift movements of said platen and set of type-carriers, said stop-device including two pairs of opposite 50 individual stops, and, for sound-muffled engagement with said two stops, resilient abutment-elements, each presenting a supportable formation terminating in two spaced parallel abutment-surfaces, one for each individual stop, said abutment-surfaces being inclined to said formation, and inclined supporting means arranged to 55 receive said formation to retain said abutment-elements, so that said abutment-surfaces extend beyond the supporting means and transversely of and between opposite individual stops, to coact quietly with the latter, the abutment-elements being independently adjustable along said inclined supports, and the faces of the stops and 60 the faces of the abutment-surfaces being parallel at all adjustments.
6. In a typewriter including a revoluble platen and a set of type-carriers, each type-carrier having upper and lower case types; an adjustable stop-device for quietly arresting the opposite relative case-shift movements of said platen and set of type-carriers, said stop-device including two pairs of opposite stops, and adjustable abutment-elements, each having two spaced resilient 65 abutment-surfaces, one for each individual stop,
- 70

and supporting means upon which the abutment-elements are adjustable, said abutment-surfaces extending beyond the supporting means and transversely of and between opposite individual stops, to coact with the latter, each of said abutment-elements being adjustable as a unit to adjust its two abutment-surfaces simultaneously and equally in either direction of case shift, thereby to determine the position of the printing line on the platen for both the upper and lower case types.

7. In a case-shifting stop-mechanism for a typewriting machine, the combination with a carriage, a platen, and a shiftable platen-frame, of a horizontal main abutment or stop mounted upon an inclined mount at each end of the carriage, either main stop being adjustable independently along its inclined mount to raise or lower the main abutment and platen at either end, and a pair of individual stops mounted on each end of the platen-frame, for individual up and down independent adjustment, for co-operation with said main abutments to arrest the platen-frame; whereby, after the platen-frame stops have been individually adjusted, any desired bodily readjustment of the platen-frame and platen at either end may be secured, without disturbing any individual platen-stop adjustment, by a lifting or lowering readjustment of one or both of the main abutments along their inclined mounts. 30

8. In a case-shifting stop-mechanism for a typewriting machine, the combination with a carriage, a platen, and a shiftable platen-frame, of a horizontal main abutment or stop mounted upon an inclined mount at each end of the carriage, either main stop being adjustable independently along its inclined mount to raise or lower the main abutment and platen at either end, a pair of individual stops mounted on each end of the platen-frame, for individual up and down independent adjustment, for co-operation with said main abutments to arrest the platen-frame; whereby, after the platen-frame stops have been individually adjusted, any desired bodily readjustment of the platen-frame and platen at either end may be secured, without disturbing any individual platen-stop adjustment, each of said abutments being in the form of resilient horizontal ends of an inclined loop, and each of said mounts being arranged to present a pair of inclined slots on said carriage in which the loop may slide, and means for fastening each loop where adjusted.

9. In a case-shifting stop-mechanism for a typewriting machine, the combination with a carriage, a platen, and a shiftable platen-frame, of a horizontal main abutment or stop mounted upon an inclined mount at each end of the carriage, either main stop being adjustable independently along its inclined mount to raise or lower the main abutment and platen at either end, a pair of individual stops mounted on each end of the platen-frame, for individual up and down independent adjustment, for co-operation with said main abutments to arrest the platen-frame; whereby, after the platen-frame stops have been individually adjusted, any desired bodily readjustment of the platen-frame and platen at either end may be secured, without disturbing any individual platen-stop adjustment, each of said abutments being in the form of re- 75

- silent horizontal ends of an inclined loop, and each of said mounts presenting a loop-embracing inclined slot on said carriage in which the loop may slide, and means for fastening each loop where adjusted, a filler-block being inserted in each loop to support it, said fastening means including a screw-clamp for fastening together the main abutment, filler-block and carriage.
10. Machine constructed according to claim 7, in which the individual platen-frame stops are in the form of two pairs of upper and lower screws, and pairs of jaws are fastened to the platen-frame ends, each pair of jaws to receive a pair of said screws.
15. 11. Machine constructed according to claim 7, in which the individual platen-frame stops are in the form of two pairs of upper and lower screws, and pairs of jaws are fastened to the platen-frame ends, each pair of jaws to receive a pair of said screws, said jaws being provided with means for securing the screws where individually adjusted.

12. In a typewriter, the combination with a frame shiftable for effecting relative case-shift movements of a platen and upper and lower case types, of a universally adjustable case-shift stop mechanism for said frame including a pair of stops, a counter-stop device for coacting with said stops according to the case shifts of said frame, means for relatively adjusting said stops and counter-stop device to determine the extent of case-shift movement, and means separate from said adjusting means for relatively adjusting said stops and counter-stop device without affecting the adjustment for the extent of case-shift movement, whereby the positions of the platen relative to the printing line for both upper and lower case types may be trued independently of the adjustment for the extent of case-shift movement.

ERNEST M. R. BORG. 20
